UNITED STATES PATENT OFFICE.

PERCY CLOUGH, OF KEIGHLEY, ENGLAND.

FLIER FOR SPINNING, TWISTING, DOUBLING, AND ANALOGOUS MACHINES.

Application filed August 14, 1922. Serial No. 581,713.

To all whom it may concern:

Be it known that I, PERCY CLOUGH, subject of the King of Great Britain, residing at Grove Mills, Keighley, Yorkshire, England, have invented certain new and useful Improvements Relating to Fliers for Spinning, Twisting, Doubling, and Analogous Machines, of which the following is a specification.

10 This invention relates to fliers for spinning, twisting, doubling and analogous machines, and it has for object to prevent the thread from escaping from the flier during the doffing operation, as often occurs especially when mechanical doffing apparatus is employed.

Accordingly, instead of having the usual "twizzle" thereon, each leg of a flier terminates in a gapped ring arranged thereon in such manner as to permit the thread to take the usual angle relatively to the flier leg and so fashioned that the thread is trapped and is impeded from escaping accidentally from the ring.

25 The invention is illustrated by way of example in the accompanying drawings, in which Figure 1 is a front elevation and Figure 2 is a side elevation of a flier, the latter view showing at one side the passage freed 30 for the introduction of the thread.

The flier consists of a horizontal member A for attachment to a spindle, and two legs a, a, which terminate in rings b, b located in a plane at right angles to that in which 35 the body of the flier lies and formed at cranked or offset extremities of the legs.

Each ring b is gapped or formed with a passage extending through the wall thereof as at c (Figure 2) said gaps or passages c 40 facing in opposite directions.

That portion of the ring b adjacent the gap c is formed by two cylindrical studs d, d, placed in axial alignment and whereof the opposed ends are spaced sufficiently 45 apart to permit of the passage of the thread therebetween, the lower of said studs being shorter than the upper. A tubular member e is fitted loosely over said studs d and is of such a length as normally to cover the 50 spaced ends but is capable of being slid upwardly to uncover the gap c when it is desired to insert the thread in the ring.

Normally the tubular member e rests on the lower member of a ring b as shown to 55 the left of Figure 2.

The tubular member e may either be seamless, in which case it would be fitted in place during the shaping of the ends of the flier legs, or said tubular member may be jointed and could then be removed and renewed 60 without unbending a ring b.

It will be seen that by means of the invention once the thread has been inserted into a ring it is extremely unlikely to escape therefrom, even when the threads are 65 being manipulated by mechanical doffing apparatus, and consequently the inconvenience and delay which are frequently experienced owing to threads escaping from the usual "twizzles" will be obviated.

What I claim is:—

1. A flier for a spinning, twisting, doubling and analogous machine, comprising a horizontal member for attachment to a spindle, two legs depending from said horizontal member, a gapped ring at the foot of each leg for the reception of thread to be laid on to a bobbin, each gapped ring being offset from the vertical plane of each leg, and movable means on each gapped ring to 70 trap the thread therein to impede same from escaping accidentally therefrom.

2. A flier for a spinning, twisting, doubling and analogous machine, comprising a horizontal member for attachment to a spindle, two legs depending from said horizontal member, said legs being offset at their lower extremities, a gapped ring disposed vertically below each of said offset extremities for the reception of thread to be laid on to a bobbin, said gapped rings being located in planes at right angles to the plane in which the flier lies and both facing in the same direction, and movable means on each gapped ring to trap the thread therein to 80 impede same from escaping accidentally therefrom.

3. A flier for a spinning, twisting, doubling and analogous machine, comprising a horizontal member for attachment to a spindle, two legs depending from said horizontal member, said legs having offset portions at their lower extremities, a gapped ring disposed vertically below each of said offset portions for the reception of thread to be laid on to a bobbin, said gapped rings being located in planes at right angles to the plane in which the flier lies and both facing in the same direction, a pair of studs arranged in 90 axial alignment on each of said gapped 95

100 spaced ends but is capable of being slid upwardly to uncover the gap c when it is desired to insert the thread in the ring.

Normally the tubular member e rests on the lower member of a ring b as shown to 110 the left of Figure 2.

rings, the opposing ends of said studs being spaced apart a distance sufficient to permit of the passage of thread therebetween, and a tubular member slidably mounted on the 5 pair of studs on each ring for covering and uncovering the space between said studs.

In testimony whereof I have hereunto set

my hand in presence of two subscribing witnesses.

PERCY CLOUGH.
